UNITED STATES PATENT OFFICE.

WILLIAM O. BENNER, OF LEHIGHTON, PENNSYLVANIA.

GRAVITY-MOTOR.

SPECIFICATION forming part of Letters Patent No. 702,086, dated June 10, 1902.

Application filed June 28, 1901. Serial No. 66,425. (No model.)

To all whom it may concern:

Be it known that I, WILLIAM O. BENNER, a citizen of the United States, residing at Lehighton, in the county of Carbon, State of Pennsylvania, have invented certain new and useful Improvements in Gravity-Motors; and I do hereby declare the following to be a full, clear, and exact description of the invention, such as will enable others skilled in the art to which it appertains to make and use the same.

This invention relates to gravity-motors; and it has for its object to provide an apparatus wherein a weight may be raised to a suitable elevation and then permitted to descend, so that the energy thereof may be utilized for sawing wood, for churning, or for any other purpose where power is required.

In the drawings forming a portion of this specification, and in which like numerals of reference indicate similar parts in the several views, Figure 1 is a side elevation showing the complete machine. Fig. 2 is a section on line 2 of Fig. 1 and showing the arrangement of the gearing with the governor and brake mechanism. Fig. 3 is a vertical transverse section through the weight-box.

Referring now to the drawings, the mechanism is mounted upon a suitable base 5 and comprises a tower or frame, including parallel uprights 6 of angle-plates, the sides of which are connected by cross-pieces 7 to form a rectangular frame, and the uppermost cross-pieces support a shaft 8, on which is disposed a pulley-wheel 9. One end of a cable 10 is attached to a bale 11 of a weight-box 12, while the opposite end of the cable is attached to a winding-drum 13, carried by a drum-shaft 14, mounted in bearings in suitable supports, as shown. The cable between its ends is passed over the pulley and downward through a guide-passage 14, formed through the bottom of the weight-box and having upwardly-extending walls in the form of a flattened tube, so that the cable may have a lateral movement through the weight-box as it is wound upon or unwound from the winding-drum. If the winding-drum is rotated, the cable will be wound thereon to raise the weight-box, and if the drum be then released the box will descend and by its descent will unwind the cable from the drum to rotate the latter. The drum is mounted loosely upon its shaft and at one end

thereof is a gear-wheel 15, having a pawl 16, pivoted thereon in operative relation with a ratchet-wheel 17, fixed upon the drum-shaft, 55 the pawl being held in engagement with the ratchet-wheel by means of a spring 18. A winding-shaft 19 is provided and is mounted both for rotatable and sliding movement in bearings upon the base and carries a pinion 60 20 for engagement with the gear of the winding-drum. The pinion is held normally out of engagement with the gear by means of a helical spring 22 upon the winding-shaft, one end thereof bearing against a shoulder on the 65 shaft, while the other end bears against one of the supports of the shaft. By pressing the winding-shaft against the tendency of the spring it will be engaged with the gear on the drum, and by then rotating it the drum will 70 be rotated to wind up the cable and raise the weight-box. The pawl-and-ratchet arrangement permits of rotation of the drum independently of the shaft to wind up the cable; but reverse movement of the drum can be 75 made only with the shaft.

Fixed upon the drum-shaft 14 and at the opposite side of the drum from the gear-wheel 15 is a master-gear 24, which engages with a pinion 25 on a shaft 26, this pinion having 80 also a gear 27 engaged therewith, which is mounted upon a shaft 28, carrying a band-wheel 29, from which leads a band 30 to one member 31 of a cone-pulley, mounted on the power or drive shaft 32, the second and larger 85 member 32 of which is adapted to receive a belt to drive any mechanism that is to be operated.

The pinion 25, above referred to, forms an element of a second train of gearing, which 90 includes a gear 33, mounted on the pinion-shaft, and which through the medium of the pinions 36 and 37 and 38 and the gears 39 and 40 rotates the governor-shaft 41, which carries the pinion 38, this governor-shaft being 95 rotated with a high rate of speed. The governor consists of a disk 42, which is fixed upon the shaft 41, and a second disk 43, which is mounted slidably upon the shaft, and these two disks are connected by means 100 of the spring-plates 44 and 45, which carry weights 46 and 47 at points midway of their end, and which weights are movable outwardly by centrifugal force to draw the mov-

able plate in the direction of the fixed plate, as will be understood. Mounted slidably upon the shaft 41 is a sleeve 48, having radiating arms 49 and 50, which extend radially 5 of the movable plate, adjacent to one face thereof, and the ends of these arms are bent around the edge of the movable plate and then inwardly to lie parallel with the opposite face thereof, and these ends are provided 10 with brake-shoes 51 in the path of movement of the movable disk, so that when the disk is drawn along the shaft 41 it will bear against the brake-shoes with a pressure depending upon the centrifugal action of the weights 15 and which action is of course commensurate with the speed of rotation of the shaft. In this way the speed of rotation of the shaft is governed and therewith the speed of the winding-drum and the speed of the driving 20 cone-pulley. The sleeve that carries these brake-shoes may be shifted to apply the brakes to stop the apparatus by shifting the lever 53, which is pivoted upon a standard, as shown, and which has a yoke 54 at one end, 25 which embraces and is pivoted to the shaft. It will thus be seen that the speed of rotation of the apparatus is governed, and it will be understood that the lever referred to may be employed for both stopping the mechanism 30 and releasing it to permit it to operate.

With this construction it will be seen that cone-pulleys of various sizes may be employed and that pulleys 29 of different sizes may be employed to get different speeds of 35 the power-shaft 32' without requiring adjust-

ment of the governor mechanism, which adjustment would be required if the governor were driven from the shaft 32'.

It will be understood that in practice modifications of the specific construction shown 40 may be made and that any suitable materials and proportions may be used for the various parts without departing from the spirit of the invention.

What is claimed is—

45

1. A device of the class described comprising a potential device including a winding-drum, a drive-shaft operatively connected with the drum, a governor for the potential device operatively connected with the drum 50 and means for actuating the governor manually to stop and release the mechanism.

2. A device of the class described comprising a potential device including a winding-drum, a drive-shaft operatively connected 55 with the drum, a governor for the potential device including an automatically-shiftable brake member, a brake-shoe in the path of movement of the shiftable member, and means for manually moving the shoe into and 60 out of engagement with the shiftable member to stop and release the mechanism.

In testimony whereof I hereunto sign my name, in the presence of two subscribing witnesses, on the 29th day of April, 1901.

WILLIAM O. BENNER.
